COMBINATION MEDICAL SUPPLY CART AND CABINET

Lloyd J. Oye, 6714 Crest Road W., Palos
Verdes, Peninsula, Calif. 90274

Filed Aug. 8, 1968, Ser. No. 13,063

Term of patent 14 years

Int. Cl. D12—02; D24—02

U.S. Cl. D14—3

Fig. 1

Fig. 2

Fig. 4

Fig. 3

FIG. 1 is a front perspective view of a combination medical supply cart and cabinet, showing my new design;

FIG. 2 is a rear perspective view thereof;

FIG. 3 is a front elevation thereof;

FIG. 4 is a side elevation thereof;

FIG. 5 is a front perspective view thereof, with the cabinet doors in an open position;

FIG. 6 is a front perspective view of a second modified embodiment of the medical supply cabinet disclosed in FIG. 5;

FIG. 7 is a front perspective view of a third embodiment of the medical supply cabinet disclosed in FIG. 5; and

FIG. 8 is a front elevation of the embodiment disclosed in FIG. 6.

What is claimed is:

The ornamental design for a combination medical supply cart and cabinet, as shown and described.
